CLAIM

The ornamental design for a printer as shown and described.

DESCRIPTION

FIG. 1 is a perspective view of a first embodiment of the printer;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a perspective view of a second embodiment of the printer;

FIG. 9 is a front elevational view thereof;

FIG. 10 is a rear elevational view thereof;

FIG. 11 is a left-side elevational view thereof;

FIG. 12 is a right-side elevational view thereof;

(Continued)

FIG. 13 is a top plan view thereof; and,
 FIG. 14 is a bottom plan view thereof.
 The evenly spaced broken lines depict portions of the printer
 that form no part of the claimed design.

1 Claim, 14 Drawing Sheets
